[57] **CLAIM**

The ornamental design for a video camera combined with video tape recorder, as shown and described.

DESCRIPTION

FIG. 1 is a front elevational view of a video camera with video tape recorder showing my new design;

FIG. 2 is a left side elevation view of the video camera of FIG. 1;

FIG. 3 is a rear elevation view of the video camera of FIG. 1;

FIG. 4 is a right side elevation view of the video camera of FIG. 1;

FIG. 5 is a top plan view of the video camera of FIG. 1;

FIG. 6 is a bottom plan view of the video camera of FIG. 1;

FIG. 7 is a front perspective view of the video camera of FIG. 1;

FIG. 8 is a rear perspective view showing the video camera door in a partially open position;

FIG. 9 is a perspective view similar to FIG. 8 showing the video camera door in a fully opened position; and,

FIG. 10 is a rear elevation view showing the video camera of FIG. 1 in operating condition with an LCD display showing an indicia.
